UNITED STATES PATENT OFFICE.

ARNOLD LARSEN, OF INDIANAPOLIS, INDIANA.

OIL BURNER.

1,403,697.

Specification of Letters Patent. Patented Jan. 17, 1922.

Application filed October 21, 1920. Serial No. 418,522.

To all whom it may concern:

Be it known that I, ARNOLD LARSEN, a citizen of the United States, residing at Indianapolis, in the county of Marion and 5 State of Indiana, have invented certain new and useful Improvements in Oil Burners, of which the following is a specification.

This invention relates to oil burners, and is designed primarily for use in connection 10 with boilers of steam propelled vehicles, although it will be understood that it may be used for producing heat for various purposes. One feature of the invention is the provision of a plurality of associated tubes 15 and valves for controlling the passage of the fuel from a supply tank to the combustion chamber, said tubes being so arranged that the fuel will be vaporized before being discharged into the combustion chamber.

20 A further feature of the invention is the provision of a burner so constructed that back firing will be practically eliminated while at the same time the most efficient passage for the fuel into the combustion chamber will be provided.

A further feature of the invention is the provision of a pilot so constructed that a sufficient temperature will be maintained below the vaporizing tube to instantly vaporize 30 the fuel when turned into said tube, a minimum amount of fuel being used for keeping the vaporizing tube hot.

A further feature of the invention is the provision of means for removing any collection of sediment at the ends of the fuel discharge nozzles.

Other objects and advantages will be hereinafter more fully set forth and pointed out in the accompanying specification.

40 In the accompanying drawings which are made a part of this application,

Figure 1 is a top plan view of the burner as applied to use in connection with the boiler of a motor propelled vehicle,

45 Figure 2 is a sectional view thereof as seen on line 2—2 Figure 1,

Figure 3 is a transverse sectional view through the burner as seen on line 3—3 Figure 2,

50 Figure 4 is an enlarged longitudinal sectional view through the fuel conveying and vaporizing structure, and

Figure 5 is a sectional view as seen on line 5—5 Figure 4.

55 Referring to the drawings in which similar reference numerals designate correspond-

ing parts throughout the several views, 1 indicates a boiler which is in this instance shown as circular and is designed to be used in connection with automobiles or similar 60 steam propelled vehicles, and to the lower end of said boiler is attached a burner comprising a casing the upper end of said casing being open while the lower portion thereof is provided with a tubular mixing tube 3 65 through which fuel is introduced in the lower portion or mixing chamber of the casing. The interior of the casing 2 is provided with a flange 4 which is designed to support bars 5, said bars being spaced apart to form slots 70 6 for the passage of the fuel from the lower portion of the casing. In order to prevent the bars 5 from becoming so heated that a back fire or explosion of the fuel would occur in the mixing chamber or the lower portion of the casing 2, said bars are preferably 75 formed of channel iron and the channels filled with fire clay 7 or other heat resisting substance, consequently the lower portions of the bars will be prevented from reaching 80 such a temperature as to ignite the fuel below the bars.

The fuel is conveyed from any suitable source of supply through a tube 8 into a tubular vaporizing chamber 9, the fuel being 85 vaporized while passing through the chamber 9, and is conveyed to a valve 10 through a pipe 11, said valve having a nozzle 12 thereon which discharges the fuel into the outer open ends of the mixing tube 3 and 90 from whence it passes into the casing 2 below the bars 5, the fuel being properly commingled with air as it passes through the mixing chamber. The valve 10 is controlled by a needle 13, said needle having a shoulder 95 14 thereon which engages a shoulder 15 on the interior of the valve 10, said shoulders being positioned a distance from the discharge end of the nozzle, and to prevent any accumulation of sediment at the discharge 100 end of the nozzle the needle 13 is provided with an extension 16 which is more or less blunt at its outer end, and consequently removes any sediment that may collect in the discharge opening of the nozzle when the 105 needle is turned inwardly its full distance.

The fuel to the pilot is conveyed from the same source as the fuel for the burner proper and is entered into a cylindrical chamber 17 through a pipe 18, the cylindrical chamber 110 17 extending longitudinally through the vaporizing chamber 9, and beyond one end

thereof, the latter chamber being of less diameter than the vaporizing chamber so as to form a thin film clearance space entirely around the chamber 17, consequently the fuel 5 will be maintained in a thin film so that it will be quickly vaporized.

The fuel passing through the cylindrical chamber 17 is also spread into a thin film by entering a tube 19 longitudinally through 10 the said cylinder, the inner end of the tube being closed and spaced from the end of the cylinder member 17, the outer end of the tube 19 projecting beyond the cylinder 17 and being open so that any suitable heating 15 element may be entered into said tube, if desired.

A valve 20 similar in detail to the valve 10 is connected with the cylindrical chamber 17, the vaporized fuel passing from said 20 chamber through an extension 21, and through the valve 20 into a pilot burner 22, said pilot burner being positioned immediately below the heating chamber 9 and extends longitudinally of the heating chamber 25 and substantially from end to end thereof.

The open end of the pilot 22 has a mixing chamber 23 for properly mixing air with the fuel as it is discharged from the nozzle 20. 30 The pilot burner 22 has a plurality of slots 24 through which the fuel passes before it is ignited. The heat from the pilot maintains the temperature within the heating elements 9 and 17 at such a degree as to vaporize the fuel and also produces sufficient heat to prevent water within the boiler from freezing during cold weather, and at the same time reducing consumption of the fuel to a minimum. The pilot also serves to ignite the 35 fuel entering between the slots 6 of the burner.

The bars 5 may be very cheaply manufactured and the ends are rested upon the flange 4 and secured thereto by rivets 25 or in any 45 suitable manner. The casing portions of the burner may also be very cheaply manufactured as it can be molded, if desired, or the parts thereof may be made up of sheet metal, if preferred. Consequently, the envelope 50 structure may be very cheaply manufactured and will be unusually strong and durable, the fire clay entered in the chamber portions of the bars 5 fully protecting the bars from the intense heat, consequently prolonging the life of the bars.

The pipes 8 and 18 are provided with a valve 26 and 27 so that the fuel may be cut off from either of the heating members or from both of them, as may be desired.

60 As best shown in Figure 4 the chamber 17 containing the fuel for the pilot is enclosed by the chamber 9 containing the fuel for the burner proper, consequently the heat for vaporizing the fuel in the inner tube or chamber 17 has to pass through the wall of the

outer chamber 9, consequently the chamber 9 is heated to such a high degree that when the raw fuel is admitted thereto by opening the valve 26, it will be thoroughly vaporized and practically instantly, or before it reaches 70 the discharge pipe 11. This obviates any possibility of the fuel being discharged into the mixing chamber in raw or unvaporized condition, and eliminates discharges of offensive smoke and odors. 75

Under ordinary usage the pilot remains lighted thereby maintaining such a temperature that it requires but a minimum amount of time to increase the steam pressure to the required capacity and all that is necessary 80 to apply the burner to use is to open the valve 26 so that the fuel will pass into the vaporizing chamber 9 where it is instantly vaporized, and passes downwardly through the valve 10, thence upwardly between the 85 bars 5, the blaze from the pilot igniting the gaseous fuel as it passes above the bars.

It will likewise be seen that by employing the spaces between the bars as the openings for the passage of the fuel, a large burning 90 surface is provided, consequently an intense heat can be produced in a very short space of time. Furthermore, it will require less fuel to maintain the proper heat below the boiler after the maximum temperature has 95 been reached.

Having thus fully described my said invention, what I claim as new and desire to secure by Letters Patent, is:

1. In a burner, a casing, a fuel mixing 100 chamber in the lower portion of said casing, a pilot burner extending transversely through the casing, and a plurality of bars channel-shaped in cross section above said mixing chamber, said bars being spaced 105 apart to form fuel openings therebetween, said pilot displacing and forming a substitute for one of said bars.

2. In an oil burner, a casing having a fuel mixing chamber in the lower portion 110 thereof, a pilot burner in a plane above said mixing chamber, fuel conveying chambers above said pilot, and a plurality of bars substantially channel-shaped in cross section in line with said pilot burner and spaced 115 apart to form slots for the passage of the fuel from the lower portion of the casing, said pilot displacing one of said bars.

3. In an oil burner, a casing, a plurality of bars within the casing and dividing the 120 interior of the casing into a mixing chamber and a combustion chamber, said bars being spaced apart to form passages for the fuel from the mixing chamber, and heat resisting means on said bars to prevent the lower portions of said bars from reaching a high degree of temperature.

4. In an oil burner, a casing, a plurality of bars extending transversely of the interior of the casing and spaced apart to form 130

fuel passages, said bars being substantially channel-shape in cross section, and heat resisting means within the channel portions of the bars for reducing the temperature of the lower portions of the bars.

5. In an oil burner, a casing, a plurality of chamber forming tubes extending transversely through the casing and one within the other so spaced apart that the fuel passing therethrough will be in thin films, means for regulating the flow of fuel into said chambers, means for providing heat of sufficient intensity to instantly vaporize the fuel

as it is entered in the outer tube and also vaporize the fuel in the inner tube, and 15 valves for controlling the passage of the fuel from said chambers into the burner.

In witness whereof, I have hereunto set my hand and seal at Indianapolis, Indiana, this 18th day of October, A. D. nineteen hundred 20 and twenty.

ARNOLD LARSEN. [L. s.]
